UNITED STATES PATENT OFFICE.

AUGUST LEIB, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

RADIO DIRECTION FINDER.

Application filed August 8, 1922. Serial No. 580,515.

To all whom it may concern:

Be it known that I, AUGUST LEIB, a citizen of Germany, residing at 12/13 Hallesches Ufer, Berlin, Germany, have invented certain new and useful Improvements in Radio Direction Finders; and I do hereby declare the following to be a full, clear, and exact description of the invention, of which the following is a specification, and on which an application was filed in Germany, May 24, 1921, No. G. 53,945.

For determining the location of a receiver or the direction of a transmitter therefrom receivers have heretofore been employed which were provided with a rotatable frame shaped antenna. This frame shaped antenna was supported for rotation about a fixed axis, and the receiver, when installed on vehicles, ships and the like, had the disadvantage that in an inclined position of the vehicle or vessel, the axis departed considerably from the vertical direction, thus giving rise to geometrical mistakes in the reading of the instrument.

According to the present invention, this disadvantage is overcome by arranging the frame shaped antenna, inclusive of all parts which are affected by the incoming waves, such, for example, as coupling coils and tuning means, to turn on an axis, and by so supporting the turning axis as to cause it to always assume a vertical position, even when the case vehicle or vessel on which the receiver is installed occupies an inclined position.

This can be attained by supporting the frame shaped antenna on a universal bearing and suitably weighting it. The means for tuning the antenna can in this case be used as a weight.

In one practical embodiment of the invention, the frame shaped antenna is fitted with a ball or other spherically curved pivot which allows free movement of the antenna towards all sides and its automatic adjustment into the vertical position, as well as its turning.

The pivot can be arranged either above or below the antenna. In the latter case a counter weight is connected to the axis of the antenna in order to obtain a stable equipoise.

The pivot is preferably arranged with its centre of curvature coinciding with

centre of the antenna frame, so that when the vehicle or ship is moving the antenna describes only a rotation about its centre in maintaining its vertical position.

The pivot member forming the bearing for the frame shaped antenna is comparatively very large and provided with a scale, while on the frame a pointer is mounted cooperating with this scale.

In order to better explain the invention, Figs. 1 to 5 of the drawings show, by way of example, several of its practical embodiments.

In Fig. 1 of the drawings,

1 is a frame shaped antenna in which tuning means 2 is arranged. 3 is a ball which acts as a pivot for the antenna 1. The ball is provided with a scale 4 and rests on smaller balls 5 which are arranged in a seat formed in the antenna support 6 to form a ball bearing. The ball is mounted on the axis 7 of the antenna, and fixed to the lower end of the axis 7 is a counter weight 8. 9 is a pointer secured to the support 6 and cooperating with the scale 4. The support 6 is formed with feet 10 which may be rigidly connected to the floor 11, 12 of a vessel or other vehicle. The mode of action of the device is evident from the drawing. In every position of the floor indicated by the line 11, 12, the antenna 1 will assume a vertical position in consequence of the effect of the counter weight 8.

The arrangement according to Fig. 2 is the same with the only exception that the ball pivot is arranged above the frame shaped antenna. In this arrangement the counterweight may be omitted as the antenna together with the receiving apparatus 2 acts as a stabilizing weight.

The arrangement according to Fig. 3 is fitted with a spherically curved pivot 3 of such a design that its centre of curvature coincides with the centre of the antenna 1. The advantage of this expedient can readily be seen. The entire vehicle, when it rocks or changes position, moves relatively to the center of the antenna 1 in a circular path about the center of the antenna 1 as a center of curvature. Thus it will be seen that all points on the vehicle, even tho they shift position relative to the antenna, maintain constant distances therefrom thus maintaining the capacitance between the antenna and the vehicle constant.

irrespective of the position of the vehicle.

In Fig. 4 an arrangement is shown in which the antenna coil 1 is located above deck and the counterweight below deck. The counterweight is suitably formed by the receiving apparatus 2 to which are connected relays 14 and a battery 15 by means of a cable strand 13. The antenna frame is also in this case supported by the ball bearing 3, 5. The ball bearing 3, 5 is provided in the support 6 and is covered by a cap 16. This cap may be provided with a scale 4 on which plays a pointer 9 attached to the support.

15 In Fig. 5, an arrangement is shown in which the antenna 1 is located above the deck and receiving apparatus 2, acting as a counterweight is located below deck. Both the antenna and receiving apparatus are mounted on the shaft or axis 7 which in turn is supported by means of a universal bearing having its center of curvature coincident with the center of antenna 1 as is in Fig. 3.

25 The cap 16 is fixed to axis 7 and is provided with a scale 4 to coact with the pointer 9 fixed to support 6.

I claim as my invention:

30 1. A radio device comprising a frame-shaped antenna, a rotatable axis upon which the antenna is mounted, a support for the antenna having an opening for said axis of substantially greater diameter than the axis, and a spherically curved member fixed to said axis and seated upon the support so as to allow said axis to swing laterally in all directions and thereby cause it automatically to assume a vertical position regardless of inclination of the support.

40 2. A radio device comprising a frame-shaped antenna, an axis upon which the antenna is mounted, a support for the antenna having an opening for said axis of substantially greater diameter than the axis,

45 45 a spherically curved bearing member fixed to said axis below the antenna for mounting it on the support, and a counter-weight on the lower end of said axis for maintaining the antenna in a condition of stable equipoise

50 with its axis in a vertical position, regardless of inclination of the support.

3. A radio device comprising a frame-shaped antenna, a rotatable axis upon which the antenna is mounted, a support for the

antenna frame adapted to be secured upon a ship or other vehicle and having an opening for said axis of substantially greater diameter than the axis, and a spherically curved bearing member for said axis having its center of curvature coinciding with the center of the antenna frame so that the axis of the antenna is maintained vertical, in case of inclination of the ship, by a turning movement about the center of the antenna.

4. A radio device adapted for installation upon the deck of a ship and comprising a frame-shaped antenna located above the deck, an axis upon which the antenna is mounted, a universal bearing for said axis for enabling it to assume a vertical position regardless of inclination of the deck in any direction, and a counter-weight secured on the axis below the deck for causing the axis to be maintained always in such vertical position.

5. A radio device comprising a frame-shaped antenna, an axis upon which the antenna is mounted, a support for the antenna having an opening for said axis of substantially greater diameter than the axis, a universal bearing for said axis for enabling it to assume a vertical position regardless of inclination of the support, receiving apparatus mounted on the axis below said bearing and serving as a counter-weight for maintaining the axis in its vertical position.

6. A radio device comprising a frame-shaped antenna, an axis upon which the antenna is mounted, a support for the antenna having an opening for said axis of substantially greater diameter than the axis, a universal bearing for said axis for enabling it to assume invariably a vertical position, and a cap fixed on the axis above the bearing, said cap and said support being provided with a co-operating scale and pointer.

7. A radio device comprising an antenna, a support for said antenna adapted to be mounted on a vehicle subject to rocking, and means for maintaining the said antenna in a fixed direction and for insuring that any given parts of the vehicle shall be always at a constant distance from said antenna, irrespective of the position of said vehicle.

In testimony whereof I have signed my name to this specification.

AUGUST LEIB.
